Eugene R. Case ATTORNEY.

UNITED STATES PATENT OFFICE.

ANDREW BROWN McLAREN, OF TORONTO, ONTARIO, CANADA, ASSIGNOR TO E. & A. GUNTHER CO. LTD., OF TORONTO, ONTARIO, CANADA.

COLLAPSIBLE BOX.

1,414,196.

Specification of Letters Patent. Patented Apr. 25, 1922.

Application filed April 14, 1921. Serial No. 461,199.

To all whom it may concern:

Be it known that I, ANDREW BROWN McLAREN, a subject of the King of Great Britain, residing in the city of Toronto, 5 county of York, Province of Ontario, Canada, have invented certain new and useful Improvements in Collapsible Boxes, of which the following is a specification.

My invention relates to improvements in 10 collapsible boxes, or containers, and the principal object of my invention is to provide great flexibility in the supporting member at the bottom of the body-portion, in all parts thereof, and so permit the same to 15 readily collapse when the body-portion is collapsed and fold in therewith, and be readily distended and made taut as the body-portion is set up, and without deterioration.

In the following specification I shall describe 20 the preferred construction of my box, and in the drawings I shall disclose the preferred shape thereof, and what I claim as new will be set forth in the claims forming part of this specification.

At the outset it must be understood that 25 I have disclosed the body-portion of my box without any covering or lining.

Fig. 1 is a side elevation of my box set up. Fig. 2 is a plan view of the body-portion alone set up, the bottom being shown 30 partly raised. Fig. 3 is a vertical cross-section on the line 3—3, Fig. 2 showing the bottom lowered. Fig. 4 is a plan view of the body-portion partly collapsed, and Fig. 35 5 is a plan view of the under side of the lid showing the collapsed body-portion nested therein.

In the drawings, like characters of reference refer to the same parts.

40 A is the body-portion of the box, and the same comprises the sides B and C associated in any manner well-known in the art. The sides C are constructed in any suitable manner each with a vertically disposed flexible 45 joint or connection D so that these sides may be collapsed to permit of the collapsing of the body-portion, as shown in Fig. 4. Each side B is provided with a flange E flexibly associated with the bottom thereof in any suitable manner, and each side C is provided 50 with a flange F suitably flexibly associated therewith. The flanges F are separated substantially midway their length as shown at G so as to permit of the collapsing of the 55 sides C. The flanges E and F are cut off at

an angle as shown at H so that these ends will not interfere when the parts are in the position shown in Fig. 2 particularly, and so permit these flanges to occupy substantially the same plane. I prefer to so shape the 60 ends of the said flanges that they will abut when the body-portion is distended.

Suitably associated with the body-portion and adapted to support the flanges E and F, is a flexible supporting member I made of 65 suitable material, preferably cotton, so that this supporting member will readily collapse when the body-portion is collapsed and fold in therewith without interference; that is to say, when the body-portion A is fully 70 collapsed the supporting member I will not interfere with the nesting of the body-portion within the lid J as shown in Fig. 5. My preferred manner of associating the supporting member I with the body-portion A 75 is to secure the edges 2 thereof around the lower edge of the body-portion A on the outer side thereof so that the said supporting member will be located underneath the flanges E and F.

80 3 is the bottom of the body-portion A and the same is flexibly associated with one of the sides B thereof in any suitable manner, preferably by means of a strip 4, of cotton, secured in place after any manner well-known in the art. The bottom 3 is shown as raised in Fig. 2. When this bottom is lowered, since it extends into contact with the sides C, it will distend or spread the said body-portion, and at the same time distend 85 the supporting member I so that when the said bottom is fully lowered, the member I will be held taut and give the desired support to the said flanges. Since the bottom 3 will also be in contact with the sides B, the distended box will be held in set-up form and possess the desired rigidity.

In order to collapse the body-portion A, the bottom 3 is raised, and then the sides C are collapsed inwardly along the joint or 90 connection D, while the flanges E and F fold against their associated sides.

95 Because of the character of the supporting member I, the same becomes substantially uniformly limp so that it will readily accommodate itself to the collapsing of the body-portion A.

The lid J will be made to retain permanently its shape, and when removed from the body-portion, when the box is of the right 110

shape, may be used as a housing for the collapsed body-portion.

Of course the shape of the box may be such that the sides may be much higher than their width.

For the purpose of clearness of illustration, I have shown the sections C' of one of the sides C, in Fig. 4, as brought close together at the top edges thus hiding the edges 2, which are broken away at the lower part of this figure so as to not confuse the illustration.

Various changes in construction may be made in that disclosed without departing from the principle of my invention, and I desire not to be limited in my scope of protection, beyond the requirements of the prior art in the terms of my claims.

While I prefer to use the strip 4 to flexibly associate the bottom 3 with one of the sides B, it must be understood that I may dispense with this strip 4 or its equivalent, if I wish.

It will be clear to one skilled in the art that the corners illustrated in Fig. 4 where the sides are flexibly associated, are greatly exaggerated for the purposes of clearness in illustration.

What I claim is:

1. In a collapsible container, a collapsible body-portion comprising flange-provided sides, one pair of opposing sides adapted to collapse inwardly, at which time the said flanges fold against their associated sides; a flexible supporting member adapted for association with the said body-portion to support said flanges when said body-portion is set up, and adapted to be collapsed substantially throughout when said body-portion is collapsed, and a movable bottom adapted, when positioned, to simultaneously distend said body-portion and said flexible support, which latter is held taut thereby.

2. In a collapsible container, a collapsible body-portion comprising flange-provided sides, one pair of opposing sides adapted to collapse inwardly, at which time the said flanges fold against their associated sides; a flexible supporting member adapted for association with the said body-portion to support said flanges when said body-portion is set up, and adapted to be collapsed substantially throughout when said body-

portion is collapsed, and a movable bottom 55
interiorly hinged near the bottom to one of the sides located between said collapsible sides, and adapted, when moved down into position, to simultaneously distend said body-portion and said flexible support, which latter is held taut thereby.

3. In a collapsible container, a collapsible body-portion comprising flange-provided sides, one pair of opposing sides adapted to collapse inwardly, at which time the said flanges fold against their associated sides; 60
a flexible supporting member exteriorly associated with lower portions of said sides and positioned to extend underneath said flanges and to support the same when said body-portion is set up, and adapted to be collapsed substantially throughout when said body-portion is collapsed; a movable bottom interiorly hinged near the bottom to one of the sides located between said collapsible sides, and adapted, when moved 65
down into position, to simultaneously distend said body-portion and said flexible support, which latter is held taut thereby.

4. In a collapsible container, a collapsible body-portion comprising flexibly associated 70
sides, each of which is provided with a flange having flexible connection therewith; one pair of opposing sides substantially midway their ends adapted to collapse inwardly, as also are the flanges associated 75
therewith; a flexible supporting member adapted for association with each of said sides to support said flanges, and a movable bottom adapted, when positioned, to simultaneously distend said body-portion and said 80
flexible support, which latter is held taut thereby.

5. In a collapsible container, in combination, a collapsible body-portion, a plurality 85
of flanges having flexible connection therewith and adapted to fold against their associated portion of said body-portion when the same is collapsed; a flexible supporting member adapted for association with said body-portion to support said flanges when 90
the container is set up, and a movable bottom adapted, when positioned, to simultaneously distend said body-portion and said flexible support, which latter is held 95
taut thereby.

ANDREW BROWN McLAREN.
